DESIGN FOR A COMBINED STAND AND ELECTRIC FAN

William W. Welch, St. Louis, Mo., and Walter A. Spear, Cincinnati, Ohio; said Spear assignor to said Welch

Application January 27, 1941, Serial No. 98,414

Term of patent 14 years

To all whom it may concern:

Be it known that we, William A. Welch and Walter A. Spear, citizens of the United States, residing, respectively, at St. Louis, in the State of Missouri, and at Cincinnati, in the county of Hamilton and State of Ohio, have invented a new, original, and ornamental Design for a Combined Stand and Electric Fan, of which the following is a specification, reference being had to the accompanying drawing, forming a part thereof.

Figure 1 is a perspective view of a combined stand and electric fan showing our new design.

Figure 2 is a side view of the device shown in Figure 1.

Figure 3 is a top plan view thereof.

We claim:

The ornamental design for a combined stand and electric fan, as shown.

WILLIAM W. WELCH.
WALTER A. SPEAR.
